FRAME FOR AUTOMOBILE LICENSE PLATES

Otto F. Baumgartner, Kansas City, Mo.

Application May 10, 1948, Serial No. 146,266

Term of patent 3½ years

(Cl. D14—6)

To all whom it may concern:

Be it known that I, Otto F. Baumgartner, a citizen of the United States, residing at Kansas City, in the county of Jackson and State of Missouri, have invented a new, original, and ornamental Design for a Frame for Automobile License Plates, of which the following is a specification, reference being had to the accompanying drawing, forming a part thereof, wherein:

Fig. 1 is a front perspective view of a frame for automobile license plates.

Fig. 2 is a rear perspective view thereof.

Fig. 3 is an end elevational view thereof; and,

Fig. 4 is a fragmentary detailed cross sectional view taken on line IV—IV of Fig. 1.

I claim:

The ornamental design for a frame for automobile license plates, as shown.

OTTO F. BAUMGARTNER.
